Henry Hufendiek
By his Atty
Mr. Randolph

United States Patent Office.

HENRY HUFENDECK, OF ST. LOUIS, MISSOURI, ASSIGNOR TO S. R. FOX,
E. G. PRATT, AND E. W. FOX, OF SAME PLACE.

Letters Patent No. 60,895, dated January 1, 1867; antedated December 12, 1866.

IMPROVED DRILL.

The Schedule referred to in these Letters Patent and making part of the same.

TO ALL WHOM IT MAY CONCERN:

Be it known that I, HENRY HUFENDECK, of the city and county of St. Louis, and State of Missouri, have invented a new and improved "Drill;" and I do hereby declare that the following is a full and exact description thereof, reference being had to the accompanying drawings, and to the letters of reference marked thereon. Of said drawings—

Figure 1 is a perspective view of said drill.

Figure 2 is a front elevation thereof, showing in red lines the possible change of gear-wheels and driving-pulley.

The nature of my invention is in the peculiar construction of a "drill" for general work, and especially in the arrangement of the parts where the power is applied, so as to admit of an application of a constant power and a constant velocity, to produce a varied power and varied velocity of the drill tool proper to the nature and size of the substance to be drilled; and lastly, the nature of my invention is the arrangement of a changeable support for the substance to be worked upon.

To enable those skilled in the art to make and use my said improved "drill," I will herewith proceed to describe its construction and operation.

I construct the parts of said drill of wrought and cast iron, or of brass or other material, varying the material according to the size of the drill itself, so as to produce the greatest efficiency by the most economical outlay of cost. The working parts of said drill are supported by the support A. This is usually cast iron and secured in a vertical position to a vertical post of the workshop or a wall of the same; but said support A may sometimes be horizontal, becoming then a bed-plate, secured by screws, bolts, or other suitable means, to a floor of the workshop. This support A has three bearings, α , α' , and α'' , for the drill-shaft and its connections. The drill-shaft B is simply held in a vertical position by the bearings α and α' . This shaft is usually wrought iron, and is turned by the bevel-wheel C or the bevel-wheel C'. The shaft B, furthermore, is moved in a vertical direction, so as to gradually lower down to the substance which is being drilled, or produce the so-called "feed" of the drill by means of a screw, b. The drill-shaft has at its lower end a socket, b, for the insertion of the drill-tool, made and arranged in the usual manner. The feed-screw b finds a bearing on the support A at α'' , which is here arranged as a nut for said screw. This screw is turned by the hand-wheel b' , and at its lower end has a swivel-head turning in the upper end of the drill-shaft b'' , so that by turning said hand-wheel b' , and thereby turning said feed-screw b, the drill-shaft B is raised or lowered. This feed arrangement may, however, consist of a feed-shaft, (instead of said feed-screw,) and a lever to actuate said feed-shaft, (instead of said hand-wheel b'), or of any other easily suggested practical arrangement. Said bevel-wheels C and C' are secured to said drill-shaft B by means of a feather moving in a vertical slot of said drill-shaft, so that said bevel-wheels may always find a support on the upper surface of said bearing α and still actuate said drill-shaft and permit the feed motion thereof, as above described. The bevel-wheels C and C' are turned by the bevel-wheel D and D', being on the same shaft, E, with the driving-wheel F; said wheel F being either a fly-wheel with hand-crank, so that man power can actuate the machine, or a simple pulley over which the belt passes, and to which the belt transmits power from the given power sources. However, if the belt and pulley be used in operating this drill it will be advantageous to tighten the belt by a simple weight-roller, so that by raising this weight-roller an extension of the belt can be made to correspond with the changes of position of the driving-pulley, (corresponding to the wheel F,) as will yet more particularly be described. The shaft E finds a bearing in the support G, which bolts on to the main support-plate A, at g and g' , when the bevel-wheels C and D are in gear with each other. Now, as the pinion C is comparatively small, it will be seen that in this arrangement a high speed of the drill-tool is attained, which for certain classes of work is preferable. In order that whenever a change of the worked substance makes it necessary, a lower speed of drill-tool be attainable, (and with the same speed of the main driving-wheel or pulley F,) the bearing G is shifted from the position marked in black lines, G, to the one marked in red lines, (fig. 2,) G'; then the shaft E is lowered to the position red E', whereby, as above stated, the belt turning a pulley at F would need a re-adjustment; then the bevel-wheel C' is placed in gear with the bevel-pinion D', and as the pinion C' is larger than C, and, moreover, as the driving-wheel D' is smaller than the driving-wheel D, it is plain that by thus changing

the shaft bearing, shaft, and wheels from the first described into the second position shown in red figures and lines in fig. 2 of the drawing, the speed of the drill-tool is moderated. It is claimed that especially in "drills" propelled and actuated by hand this arrangement for changing the speed of the drill-tool makes it possible to use one "drill," when without my said arrangement two drills would become necessary; it becomes, therefore, apparent, that by the introduction of this practicable feature there is, especially for "hand drills," here effected a valuable improvement. In order that the shifting and securing of the shaft bearing G to its other position, "red" G', may at all times be speedily accomplished, the securing screw-bolts are fixed in the main support A, at the necessary points, to wit, in correspondence with the position G, at g and g' , in correspondence with the position red G' at g and g' red. In order to support the material to be drilled, I secure just below the drill-tool the drill-table H. This table consists of several parts, to wit, of a bed-plate, h, which is secured in like manner with the main support of the machine A. This plate h has a grooved way, h', in which the table proper, i, has a vertical sliding motion, the said motion being limited to a merely vertical one by the flange pieces h'', bordering the groove h' on h. The table i is held permanently in any desired vertical distance from the drill-tool by the set-screw and nut K. Thus, by sliding i up or down, and then securing it by the set-screw and nut K, any usual size of the material to be drilled is accommodated. The table i may be arranged in variable shapes; the one shown is designed to furnish conveniences for drilling the necessary spike holes for wagon tires. The spoke of the wheel then passes between the arms i¹ and i² of said table, whereas the wheel rim rests its under (and inner) surface directly upon the arms i¹ and i². In the many uses to which my said drill may be applied the shape of the table i will be varied, suited to each specific use, but I especially claim that by providing the way h' between the flanges h'', for the reception of the vertical end piece of the table, and the set-screw and nut K, for the holding thereof properly, I have formed an improved arrangement.

Having thus described my invention, what I claim, is—

1. The combination of two or more sets of corresponding bevel gear-wheels, arranged substantially as shown by C and D, C' and D', with the changeable shaft support, when used as set forth.
2. The combination of the feed-screw b and its actuating hand-wheel b', or their equivalents, with the drill-shaft B, all supported in the bearings a, a', and a² of A, in combination with the several sets of corresponding bevel gear-wheels C and D, C' and D', &c., the changeable shaft support G, and the work-table H, as set forth.

HENRY HUFENDECK.
